UNITED STATES PATENT OFFICE.

RICHARD M. FERRILL, OF BIRMINGHAM, ALABAMA, ASSIGNOR OF ONE-HALF TO
GEO. M. LEMMON, OF BIRMINGHAM, ALABAMA.

TOY PROJECTILE WITH PARACHUTE.

Application filed March 7, 1927. Serial No. 173,471.

This invention relates to a toy projectile with a parachute secured thereto in a closed position, preferably at the back of a miniature image of a man, in combination with means which act automatically, when the toy has been propelled upward through the air to a desired height for opening the parachute to permit a slow down travel of the toy toward the ground.

10 One object of my invention is to provide a simple means for timing the opening of the parachute after the toy has been projected, a special feature of this timing means being that it will adjust itself automatically to the force by which the toy is propelled, thereby causing the parachute to open near the top of the toy's flight whether it be high or low.

A further object of my invention is to 20 provide a toy projectile having a parachute attached thereto, together with resilient releasable means for holding the parachute in folded position during a part of its flight, and timing mechanism for tripping the releasable means while the projectile is in flight.

A further object of my invention is to provide such a toy which is inexpensive, simple in construction and will not readily 30 get out of order.

My invention comprises further novel features, details of construction and combination of parts, as will be hereinafter set forth, shown in the drawings and claimed.

35 In the drawings:—

Fig. 1 is a cross-sectional view illustrating the arrangement of parts preparatory to projecting the toy with the parachute folded.

Fig. 2 is a cross-sectional view of the toy 40 descending through the air with the parachute open.

Referring to the drawing in which similar numerals of reference indicate the same parts, the miniature image of a man 3 is 45 molded or formed from any inexpensive material or composition and provided with a hole 4 to receive a tube 5 containing a piston 6 having a piston rod 7 and a compression spring 8. A U-shaped spring member 9, like a mouse trap spring having its ends 10 secured to the image 3, is employed to hold the parachute 11 in a closed position when the transverse portion of the spring member 9 is engaged by the catch lever 12 50 and the catch 13. The parachute strings or

cords 14 are connected to the transverse portion of the spring member 9 so that when the spring is released and snaps from the position shown in Fig. 1 to that in Fig. 2, the parachute is thrown outwardly and upwardly and caused to open immediately. The device is operated by fastening one end of an elastic band 15 to a throwing stick 16 and engaging its other end to a hook eye screw 17 in the head of the image 3. By 60 holding the throwing stick firmly in one hand and grasping the piston rod 7, the latter will be pulled down against the spring 8 and put the latter under tension corresponding in degree to the force exerted on the toy 65 to propel it thereby varying the movement of the piston and, as hereinafter described, automatically timing the opening of the parachute.

During the up flight of the toy projectile 70 the contracted spring 8 is free to exert its energy in moving the piston 6 toward the normal position (Fig. 2), but such motion will be counteracted by the air trapped in the upper end of the tube 5 and which is 75 allowed to escape slowly through a vent 18 in the upper end of the tube 5 and then through a larger vent 19 to the atmosphere. Near the completion of the piston's up stroke, a flange 20 on the piston rod 7 engages and releases the catch 13 which in turn 80 releases the U-shaped spring member 9 and causes it to fly up and jerk the cords 14 so as to open the parachute. It will be readily 85 observed that a heavy or light tension applied to the compression spring 8 in projecting the toy automatically times the opening of the parachute in relation to the energy exerted to produce the toy's flight.

Although I have described and illustrated 90 a particular design, construction and arrangements of parts, I do not wish to be limited thereto except as noted in the appended claims.

Having thus described my invention, what 100 I claim as new and desire to secure by Letters Patent, is:—

1. In combination with a toy projectile with a parachute, means for producing flight of the toy, automatic mechanical means for timing the opening of the parachute directly proportional to the energy used to produce the toy's flight, and spring means for throwing the opening parachute outwardly and 105 upwardly from the toy.

2. In combination with a toy projectile with a parachute, means for producing flight of the toy, automatic mechanical means for timing the opening of the parachute in relation to the energy used to produce the toy's flight, said means comprising a cylinder having a piston mounted therein, a spring associated with the piston and adapted to be flexed when producing flight of the toy a dash-pot to control the return of the piston to its normal position after the toy has been projected, a rod for the piston having a trip thereon, a catch means adapted to be released by said trip, and spring means controlled by said catch means and adapted to hold the parachute in inoperative position until released by said catch means, said spring means when released being adapted to snap open and release the parachute.
3. In a toy projectile with a parachute,

means to hold the parachute folded against the toy, a spring-pressed plunger adapted to be grasped by a hand and retracted when the toy is projected, dash-pot means to retard the spring actuated return of the plunger, and trip mechanism controlled by the return of the plunger to release the parachute.

4. In a toy projectile with a parachute, means to hold the parachute folded against the toy, a spring-pressed plunger adapted to be grasped by a hand and retarded when the toy is projected, means at the other end of the toy for attaching a projecting device thereto, dash-pot means to retard the spring actuated return of the plunger, and trip mechanism controlled by the return of the plunger to release the parachute.

In testimony whereof I affix my signature.

RICHARD M. FERRILL.
